Specification for Design.

Patented Mar. 19, 1912.

Original application filed December 11, 1909, Serial No. 532,716. Divided and this application filed December 11, 1911. Serial No. 665,158. Term of patent 14 years.

To all whom it may concern:

Be it known that I, JOHN F. KELLY, a citizen of the United States, residing at Trenton, in the county of Mercer and State of New Jersey, have invented a new, original, and ornamental Design for a Flushing-Tank for Water-Closets, of which the following is a specification, reference being had to the accompanying drawings, forming part thereof, in which—

Figure 1 is a front elevation of a tank showing my new design; Fig. 2 is a plan view of the same.

This application is a division of my prior application filed December 11th 1909, Serial Number 532,716.

I claim:

The ornamental design for a flushing tank for water closets, as shown.

JOHN F. KELLY.
